UNITED STATES PATENT OFFICE.

THOMAS B. ANDERSON, OF CHESTER, WEST VIRGINIA, ASSIGNOR TO THE EDWIN M. KNOWLES CHINA COMPANY, OF NEWELL, WEST VIRGINIA, A CORPORATION OF WEST VIRGINIA.

DESIGN FOR A DISH OR SIMILAR ARTICLE.

51,194.

Specification for Design.

Patented Aug. 28, 1917.

Application filed July 5, 1916. Serial No. 107,709. Term of patent 7 years.

To all whom it may concern:

Be it known that I, THOMAS B. ANDERSON, a citizen of the United States, residing at the city of Chester, in the county of Hancock and State of West Virginia, have invented a new, original, and ornamental Design for a Dish or Similar Article, of which the following is a specification, reference being had to the accompanying drawing, forming part thereof.

I claim:—

The ornamental design for a dish or similar article, as shown.

THOMAS B. ANDERSON.
